WIDE BAND ANTENNA

Nils E. Lindenblad, Rocky Point, N. Y., assignor
to Radio Corporation of America, a corporation
of Delaware

Application July 4, 1945, Serial No. 603,211

25 Claims. (Cl. 250—33)

1

The present invention relates to wide band antennas and, more particularly, to slot antennas adapted to be flush mounted in the skin of aircraft.

An object of the present invention is the provision of a wide band slot antenna.

Another object of the present invention is the provision of an antenna which from aerodynamic considerations is ideally adapted to aircraft use.

A further object of the present invention is the provision of a slot antenna which does not require extensive cavities beneath the skin of the aircraft.

A further object of the present invention is the provision of a slot antenna having a bandwidth of several percent.

Still a further object of the present invention is the provision of a sheet antenna which does not require isolating slots around the periphery of the radiating area.

Still a further object of the present invention is the provision of a wide band slot antenna which does not require the use of complicated compensating circuits to obtain the required band width.

Antennas of the slot type previously invented by me utilize two parallel slots in a conductive sheet, said slots being separated by a distance equal to a half of the operating wavelength. The concept involved in such antennas is that the half wave wide ribbon between the slots is resonant at the operating frequency. The high impedance slots isolate the ribbon from the surrounding surface so that only stray field currents flow in the surrounding surface, thus assuring a radiation pattern which is unusually free from deleterious side lobes.

The present invention contemplates utilizing a single feed slot in the radiating area as an energizing means for producing a radiating current pattern therein.

Since the aim with all slot antennas is to produce a surface current pattern which radiates in certain desired directions, many modifications can naturally be made without deviating from the basic principles of operation of the antenna.

In one embodiment of the present invention the half wave wide ribbon of the previous antennas may be replaced by two 90 degree triangles, having their bases connected to the central feed slot. The outer insulating cavities may then be bent around the other side of the triangles and some space conserved. A hybrid between a ribbon and a single slot antenna is thus obtained. By means of the use of a conductive

2

wedge in the coupling circuit as a connection between an edge of the slot antenna and the center conductor of a coaxial transmission line, it was found that a bandwidth of about nine percent could be obtained. The use of a more obtuse feed triangle between the antenna and the transmission line resulted in a bandwidth in excess of sixteen percent. Band width is herein based on less than 2:1 standing wave ratio on the feed line.

10 In accordance with another aspect of the present invention the size of the antenna may be further reduced by removing the outer high impedance boundary cavities. The removal of these boundary cavities does, of course, result in radiation patterns having side lobes of relatively greater magnitude since the currents in the radiating plane theoretically spread out indefinitely and thus should contribute to the formation of side lobes. The spread is however so disorganized and attenuated as far as forming standing waves from reflection at the remote free edges of the radiating sheet is concerned that the bulk of the radiation may be considered to take place from the current in the immediate vicinity 15 of the feed slot. Such patterns are acceptable except in certain exacting radar applications.

The present invention will be more fully understood by reference to the following detailed description which is accompanied by a drawing in which—

20 Figure 1 illustrates in plan view an embodiment of the present invention while Figure 2 is a sectional view taken along the line 2—2 of Figure 1.

25 Figure 3 is a curve illustrating graphically a bandwidth obtained with the antenna of Figures 1 and 2.

30 Figure 4 illustrates in plan view a modified form of the present invention while Figure 5 is a sectional view of the antenna of Figure 4, taken 35 along line 5—5, and

35 Figure 6 is a curve illustrating the bandwidth obtained by the antenna in Figure 4.

40 Figures 7 and 8 illustrate in side view and in section a further modification of the present invention.

45 Referring now to Figures 1 and 2, reference numeral 10 denotes a plane conductive surface such as the wing surface or a substantially flat part of the fuselage of an airplane.

50 A pair of 90° V-shaped or L-shaped slots 12 and 14 are cut in the conductive sheet 10, thus forming a pair of conductive triangles 18 and 20 separated by a central slot 16. On the rear surface of the conductive sheet 10 is fastened a 55 flat metal pan 22 having such dimensions as to

provide cavities 21, 23 back of triangles 18 and 20 having an effective depth of the order of one quarter of the operating wavelength. Thus, the triangles 18 and 20 are effectively isolated from the remainder of sheet 10. Back of the central slot 16 and in communication therewith is a feed chamber 24 entirely enclosed except at its point of connection with feed slot 16 and at its point of connection to transmission line TL. The dimensions of chamber 24 are so chosen that the chamber together with feed triangle 26 completes the resonance at operating frequency. The inner conductor of transmission line TL is connected to the apex of the feed triangle 26, having its base connected to one edge of feed slot 16. High frequency energy arriving through transmission line TL passes through the feed chamber 24 energizing the triangular radiating members 18 and 20 through slot 16.

From a consideration of Figure 3, wherein the curve 30 plots the standing wave ratio as ordinates against frequency change in percentages as abscissae, it will be noted that over a band extending about sixteen percent of the midband frequency, the standing wave ratio falls reasonably below 2:1.

The antenna in Figures 1 and 2 has low magnitude side lobes and is smaller than the ribbon type. It can be made smaller by capacity loading at the free ends of the triangles. The band widths will however, suffer from such procedure. However the boundary slots may be omitted for services permitting the presence of side lobes in the radiation pattern of the antenna.

The present invention including this modification is shown in Figures 4 and 5. Herein the transmission line TL feeds into a rear cavity or chamber 34 having an equilateral triangular connector 26 similar to that described with reference to Figure 2. Cavity or chamber 34 is rectangular in form having a side length of the order of .55 of the operating wavelength. It was found that radiating directly from a slot in this cavity tended to somewhat restrict the bandwidth of the antenna. Therefore, an intermediate cavity 36 is provided between the conductive sheet 10 and the feed cavity 34. These cavities or chambers are coupled together by a single diagonal slot 35. Cavity 36 is coupled to conductive sheet 10 by radiating slots 38 and 40, separated by a distance of the order of .15 of the operating wavelength. The depth of cavities 34 and 36 may be of the order of .07 of one wavelength.

Back of the strip between the slots is prismatic conductive strip 42 triangular in cross section and conductively connected to the sheet 10 at its ends. Studs 44 and 46 connect strip 42 at two separated points to the back of rear cavity 34. These studs insure that only the desired mode of oscillation can be set up within the chambers. Aside from complete mode stability a somewhat greater bandwidth is thus provided through the ability to choose proper coupling parameters between input and slots. It will be noted that due to the omission of the outer insulating cavities a considerable reduction of the cutting up of sheet 10 has been achieved while at the same time the structure has been made mechanically more rugged.

Figure 6 which is similar in nature to Figure 3 illustrates that for a bandwidth in excess of eighteen percent of the midband frequency, the antenna shown in Figures 4 and 5 has a low and

fairly constant standing wave ratio. The operating band width is indicated in the figure.

It will further be noted from Figure 6 that the antenna of Figures 4 and 5 has high pass filter characteristic. This is indicated by the way the curve of Figure 6 rises abruptly at the low frequency end of the characteristic but very slowly at the high frequency end. The usefulness of the antenna does not therefore end abruptly at the high frequency end.

Figures 7 and 8 illustrate a further modification of the invention which in effect constitutes a folding of the chambers of the modification shown in Figures 4 and 5 back to back against one another. Thus arranged, the feed chamber extends back perpendicularly to the plane of conductive sheet 10 as a pair of triangular adjacent chambers 34 and 34'. Feed chamber 34 contains an equilaterally triangular transmission line 20 coupler 26 similar to that in the modifications shown in the previous figures.

The spacing between the apex of feed triangle 26 and a side wall of chamber 34 is maintained by an insulating spacer 56. By varying the 25 length of the insulating spacer and thus the angle between triangle 26 and its adjacent wall, the spacing may be varied and thus the input impedance may be varied so as to provide a proper match between the antenna and a transmission line TL. On either side of chambers 34 and 34' are provided further similar triangular chambers 66 and 67. Chambers 66 and 67 are equivalent in their operation to chambers 21 and 23 of Figures 1 and 2 and to the single rectangular chamber 36 of Figures 4 and 5.

Feed slots 38 and 40 may be filled in by sheets of insulating material such as "Polystyrene" or one of the synthetic plastics of good dielectrical properties such as "Lucite" or methyl methacrylate. The insulating material closing slots 38 and 40 has no direct electrical function except slight capacity effects but merely prevents the entry of moisture and dirt into the resonant cavities of the antenna, thus preventing a change of characteristics due to weather conditions. Similarly, of course, the apertures in any of the previous modifications may be protected against weather conditions.

While the antennas described above have been particularly described as transmitting antennas, they may of course be equally well used for the reception of radio frequency energy, a receiver instead of a transmitter being connected to the transmission line.

While I have illustrated several particular embodiments of the present invention, it should be clearly understood that it is not limited thereto since many modifications may be made in the several elements employed and in their arrangement without departing from the spirit and scope of the invention.

What is claimed is:

1. An antenna including a conductive sheet having a pair of elongated parallel slots therein, a first rectangular chamber back of said sheet, said slots lying diagonally across said chamber, a second rectangular chamber back of said first chamber, said second chamber having a single slot therein common to both of said chambers, and means for introducing high frequency energy into said second chamber.

2. An antenna including a conductive sheet having a pair of elongated parallel slots therein, a first rectangular chamber back of said sheet, said slots lying diagonally across said chamber,

a second rectangular chamber back of said first chamber, said second chamber having a single slot therein common to both of said chambers, and means for introducing high frequency energy into said second chamber, said means including a triangular plate having its base connected along an edge of said single slot and its apex connected to a conductor of a transmission line.

3. An antenna including a conductive sheet having a pair of elongated parallel slots therein, said slots having a length of substantially 0.65 wavelength at the operating frequency, a first rectangular chamber back of said sheet, said slots lying diagonally across said chamber, a second rectangular chamber back of said first chamber and having a single slot connecting both of said chambers, and means for introducing high frequency energy into said second chamber, said means including a triangular plate having its base connected along an edge of said single slot and its apex connected to a conductor of a transmission line.

4. An antenna including a conductive sheet having a pair of elongated parallel slots therein, said slots being spaced apart a distance equal to 0.15 wavelength at the operating frequency, a first rectangular chamber back of said sheet, said slots lying diagonally across said chamber, a second rectangular chamber back of said first chamber and having a single slot therein common to both of said chambers, and means for introducing high frequency energy into said second chamber, said means including a triangular plate having its base connected along an edge of said single slot and its apex connected to a conductor of a transmission line.

5. An antenna including a conductive sheet having a pair of elongated parallel slots therein, said slots having a length of substantially 0.65 wavelength at the operating frequency and said slots being spaced apart a distance equal to 0.15 wavelength, a first rectangular chamber back of said sheet, said slots lying diagonally across said chamber, a second rectangular chamber back of said first chamber and having a single slot therein common to said chambers, and means for introducing high frequency energy into said second chamber, said means including a triangular plate having its base connected along an edge of said single slot and its apex connected to a conductor of a transmission line.

6. An antenna including a conductive sheet having a pair of elongated parallel slots therein, a first rectangular chamber back of said sheet, said slots lying diagonally across said chamber, a second rectangular chamber back of said first chamber and having a single slot therein common to both of said chambers, and means for introducing high frequency energy into said second chamber, said rectangular chambers having a side length of substantially one-half wavelength at the operating frequency.

7. An antenna including a conductive sheet having a pair of elongated parallel slots therein, a first rectangular chamber back of said sheet, said slots lying diagonally across said chamber, a second rectangular chamber back of said first chamber, a single slot common to said chambers, and means for introducing high frequency energy into said second chamber, said rectangular chambers having a side length of 0.55 wavelength at the operating frequency and an overall depth of substantially 0.07 wavelength at said frequency.

8. An antenna including a conductive sheet

having a pair of elongated parallel slots therein, a first rectangular chamber back of said sheet, said slots lying diagonally across said chamber, a second rectangular chamber back of said first chamber and having a single slot therein common to said chambers, and means for introducing high frequency energy into said second chamber, there being a prismatic conductive strip between said slots in said first chamber.

9. An antenna including a conductive sheet having a pair of elongated parallel slots therein, a first rectangular chamber back of said sheet, said slots lying diagonally across said chamber, a second rectangular chamber back of said first chamber and having a single slot therein common to both of said chambers, and means for introducing high frequency energy into said second chamber, said rectangular chambers having a side length of 0.55 wavelength at the operating frequency and an overall depth of substantially 0.07 wavelength at said frequency, there being a prismatic conductive strip between said slots in said first chamber.

10. An antenna including a conductive sheet having a pair of elongated parallel slots therein, a first rectangular chamber back of said sheet, said slots lying diagonally across said chamber, a second rectangular chamber back of said first chamber and having a single slot therein common to said first and second chambers, and means for introducing high frequency energy into said second chamber, said means including a triangular plate having its base connected along an edge of said single slot and its apex connected to a conductor of a transmission line, said rectangular chambers having a side length of 0.55 wavelength at the operating frequency and an overall depth of substantially 0.07 wavelength at said frequency, there being a prismatic conductive strip between said slots in said first chamber.

11. An antenna including a conductive sheet having a pair of elongated parallel slots therein, a first rectangular chamber back of said sheet, said slots lying diagonally across said chamber, a second rectangular chamber back of said first chamber and having a front wall in common with the rear wall of said first chamber and having a single slot therein common to said chambers, said second chamber having a rear wall, and means for introducing high frequency energy into said second chamber, there being a prismatic conductive strip having an apex and a base arranged between said slots in said first chamber and a pair of conductive studs from the apex of said strip to said rear wall of said second chamber.

12. An antenna including a conductive sheet having a pair of elongated parallel slots therein, said slots having a length of substantially 0.65 wavelength at the operating frequency and said slots being spaced apart a distance equal to 0.15 wavelength at said frequency, a first rectangular chamber back of said sheet, said slots lying diagonally across said chamber, a second rectangular chamber having a rear wall and being arranged in back of said first chamber and having a further slot interconnecting said chambers, and means for introducing high frequency energy into said second chamber, said means including a triangular plate having its base connected along an edge of said further slot and its apex connected to a conductor of a transmission line, said rectangular chambers having a side length of 0.55 wavelength at said frequency and an overall depth of substantially 0.07 wavelength

at said frequency, there being a prismatic conductive strip having an apex and a base arranged between said slots in said first chamber and a pair of conductive studs from the apex of said strip to said rear wall of said second chamber.

13. An antenna including a pair of parallel elongated slots in a plane conductive sheet, a chamber arranged in back of said slots, said chamber including two parallel triangular wall portions normal to the plane of said sheet, said chamber having the base thereof surrounding said slots, partitions within said chamber parallel to said triangular wall portions and dividing said chamber into four inner chambers side by side, said inner chambers opening together into a single area at the base of the first said chamber and a triangular plate within one of the inner chambers, the base of said triangular plate being connected to an edge of one of said partitions and a conductor of a transmission line being connected to the apex of said triangular plate.

14. An antenna including a pair of parallel elongated slots in a plane conductive sheet, a chamber arranged in back of said slots, said chamber including two parallel triangular walls arranged normal to the plane of said sheet, said chamber having the base thereof surrounding said slots, partitions within said chamber dividing said chamber into four inner chambers side by side, said inner chambers opening together into a single area at the base of the first said chamber, and a triangular plate within one of the inner chambers, the base of said triangular plate being connected to an edge of one of said partitions, a conductor of a transmission line connected to the apex of said triangular plate, and means for adjusting the spacing at the apex of said triangle from the adjacent partition.

15. An antenna including a pair of parallel elongated slots in a plane conductive sheet, a chamber arranged behind said slots, said chamber including two parallel triangular wall portions arranged normal to the plane of said sheet, said slots lying between said wall portions, partitions within said chamber dividing said chamber into four inner chambers side by side, said inner chambers opening together into a single area at the base of the first said chamber, a triangular plate within one of the inner chambers, the base of said triangular plate being connected to an edge of one of said partitions, a conductor of a transmission line connected to the apex of said triangular plate, and a prismatic conductive member between said slots within the single area in said triangular chamber.

16. An antenna including a pair of parallel elongated slots in a plane conductive sheet, a chamber arranged behind said slots, said chamber including two parallel triangular wall portions arranged normal to the plane of said sheet, said slots lying between said wall portions, partitions within said chamber dividing said chamber into four inner chambers side by side, said inner chambers opening together into a single area at the base of the first said chamber, a triangular plate within one of the inner chambers, the base of said triangular plate being connected to an edge of one of said partitions, a prismatic conductive member between said slots within the single area in said triangular chamber and connections from the apex of said prismatic member to the adjacent edge of one of said partitions.

17. An antenna including a conductive sheet

5 having at least one elongated slot therein, a resonant chamber arranged behind said slot in said sheet, a triangular plate within said chamber, said plate having its base connected to an edge of said slot and a transmission line having a conductor connected to the apex of said triangle.

18. An antenna including a conductive sheet having at least one elongated slot therein, a chamber arranged behind said slot in said sheet, a triangular plate within said chamber, said plate having its base connected to an edge of said slot and a transmission line having a conductor connected to the apex of said triangle, said chamber being so dimensioned as to be resonant to the operating frequency of said antenna.

19. An antenna including a conductive sheet having at least one elongated slot therein, conductive wall portions forming a chamber back of said sheet having an aperture in one side thereof, there being a substantially unobstructed passageway between said slot and said aperture, a triangular plate within said chamber, said plate having the base thereof connected to an edge of said aperture, and means for connecting a conductor of a transmission line to the apex of said triangular plate.

20. An antenna including a conductive sheet having at least one elongated slot therein, conductive wall portions forming a chamber back of said sheet having an aperture in one side thereof, there being a substantially unobstructed passageway between said slot and said aperture, a triangular plate within said chamber, said plate having the base thereof connected to an edge of said aperture, and means for connecting a conductor of a transmission line to the apex of said triangular plate, said chamber being dimensioned to be resonant to the operating frequency of said antenna.

21. An antenna including a conductive sheet having at least one elongated slot therein, a resonant chamber behind said slot in said sheet, a triangular plate within said chamber, said plate having its base connected to an edge of said slot and a transmission line having a conductor connected to the apex of said triangle, said sheet having V-shaped slots disposed therein with the ends of said slots juxtaposed to define a quadrangular area in said sheet with said elongated slot diagonally disposed in said area with the ends of said elongated slot adjacent the ends of said V-shaped slots.

22. An antenna including a conductive sheet having at least one elongated slot therein, a chamber behind said slot in said sheet, a triangular plate within said chamber, said plate having its base connected to an edge of said slot and a transmission line having a conductor connected to the apex of said triangle, said sheet having V-shaped slots disposed therein with the ends of said slots juxtaposed to define a quadrangular area in said sheet with the ends of said elongated slot adjacent the ends of said V-shaped slots, said chamber being dimensioned to be resonant to the operating frequency of said antenna.

23. An antenna including a conductive sheet having at least one elongated slot therein, said sheet having further V-shaped slots therein disposed therein with the ends of said slots juxtaposed to define a rectangular area in said sheet with said elongated slot diagonally disposed in

said area with the ends of said elongated slot adjacent the ends of said V-shaped slots, and means for inducing high frequency energy in the area enclosed by the edges of said elongated slot, said means comprising a chamber arranged behind said elongated slot, a triangular plate within said chamber, said plate having the base thereof connected to an edge of said elongated slot, and means to connect a conductor of a transmission line to the apex of said triangular plate.

24. An antenna including a conductive sheet having at least one elongated slot therein, said sheet having further L-shaped slots therein disposed therein with the ends of said slots juxtaposed to define a rectangular area in said sheet with said elongated slot diagonally disposed in said area with the ends of said elongated slot adjacent the ends of said L-shaped slots, chambers arranged behind said L-shaped slots, each of said chambers having a wall constituted by a portion of said conductive sheet having one of said L-shaped slots therein, said chambers having an effective depth of an odd multiple including unity of a quarter wavelength at the operating frequency, a further chamber arranged behind said elongated slot, a plane conductive member having an edge connected to an edge of said elongated slot and two other edges converging to a point, and means to connect a conductor of a transmission line to said member at said point.

25. An antenna including a conductive sheet having at least one elongated slot therein, said sheet having further L-shaped slots disposed therein with the ends of said slots juxtaposed to define a rectangular area in said sheet with said elongated slot diagonally disposed in said area with the ends of said elongated slot adjacent the ends of said L-shaped slots, chambers arranged behind said L-shaped slots, each of said chambers having a wall constituted by a portion of said conductive sheet having one of said L-shaped slots therein, said chambers having an effective depth of an odd multiple including unity of a quarter wavelength at the operating frequency, a further chamber arranged behind said elongated slot, a plane conductive member having an edge connected to an edge of said elongated slot and two other edges converging to a point, and means to connect a conductor of a transmission line to said member at said point.
